UNITED STATES PATENT OFFICE

GEORGE F. EGAN, OF JERSEY CITY, NEW JERSEY

DISPLAY DEVICE

Original application filed July 14, 1925, Serial No. 43,547. Divided and this application filed November 28, 1927. Serial No. 236,296.

This application is a division of my similarly entitled co-pending application Serial No. 43,547, filed July 14, 1925.

The present invention relates to improvements in display devices in which provision is made for conspicuously displaying a card, placard, photograph, mirror or the like.

An object of the invention is to provide a simply and inexpensively constructed holder for cards, placards, photographs, mirrors and the like in which a card, placard, photograph, mirror or the like may be easily introduced and removed, and which will protect the card and at the same time hold the card, placard, photograph, mirror or the like in a conspicuous position.

With the foregoing and other objects in view the invention will be more fully described hereinafter, and will be more particularly pointed out in the claims appended hereto.

In the drawings, wherein like symbols refer to like or corresponding parts throughout the several views:

Figure 1 is a perspective view of an improved display device constructed according to the present invention;

Figure 2 is a front elevation thereof;

Figure 3 is a vertical section taken on the line 3—3 in Figure 2; and

Figure 4 is a horizontal section taken on the line 4—4 also in Figure 2.

Referring more particularly to the drawings, the device is shown as comprising a body part 32 with a lower edge 33 and a clip 34 at one side. In addition there is shown an upper central clip 35, similar to the clip 34, which may be cut out from the metal in the apron 18 and folded downwardly. In the form of device shown in the drawings a card, placard, photograph, mirror or the like may be slid horizontally from the right toward the left into the lower edge 33 and clip 35 until it strikes the side clip 34. The card, placard, photograph, mirror or the like is then arrested in proper position and is held therein. When desired it may be readily removed from the device.

The panel or body portion 32 will preferably be provided with an opening, as 13, to

afford access to the back of the card and permit the card, placard, photograph, mirror or the like to be removed without touching or soiling its front display surface.

The lower guide or shelf 33 may be formed in one piece with the panel 32, of sheet metal or other appropriate material, by bending the lower edge of the panel outwardly and upwardly. The clip 34 may be formed in one piece with the panel 32 by bending an extension at the side edge of the panel forwardly and inwardly, but it is not necessary that the clip 34 extend the entire side edge of the panel.

The apron 18 is preferably sloped upwardly and rearwardly from the upper edge of the panel 32 and may be in one piece therewith. The downwardly extending flange 17 bent from the rear free edge of the apron 18 is adapted to permit the device to hang from a shelf or level surface. The device might also, if desired, be hung from a nail or the like by engaging the V-shaped part 35' of the flange 17 with a nail or the like, or the device may be hung on an article.

It is obvious that various changes and modifications may be made in the details of construction and design of the above specifically described embodiment of this invention without departing from the spirit thereof, provided such changes fall within the spirit or terms of the appended claims which define the invention.

What is claimed is:

1. A display device comprising a panel body having its lower edge upturned to form a sliding and supporting trough, a stop clip bent forwardly and inwardly from an intermediate portion of one side edge of the panel body, an apron extending upwardly and rearwardly from the upper edge of the panel body and having a downwardly bent flange, and a guide clip cut and bent from the material of the apron forwardly and downwardly upon the panel body.

2. A display device comprising a panel body having a channel support at its lower edge, a guide clip at its upper edge, a stop clip at one side of the body, an apron at

the upper edge of the body extending diagonally upwardly and rearwardly, and a flange extending from the upper rear edge of the apron downwardly approximately 5 parallel to the plane of the panel body.

In testimony whereof I affix my signature.

GEORGE F. EGAN.
